UNITED STATES PATENT OFFICE.

ALBERT THIRTEEN GOOKIN, OF CAMBRIDGE, MASSACHUSETTS.

CAR-FENDER.

1,114,606.

Specification of Letters Patent. Patented Oct. 20, 1914.

Application filed December 4, 1913. Serial No. 804,815.

To all whom it may concern:

Be it known that I, ALBERT T. GOOKIN, a citizen of the United States, and a resident of Cambridge, in the county of Middlesex and 5 State of Massachusetts, have invented a new and Improved Car-Fender, of which the following is a full, clear, and exact description.

My invention is more particularly intended for application to street cars, and an object of the invention is to provide a fender adapted to be swung to a raised position and held in compact form when not required for use, but which will possess such rigidity, 15 when lowered, as to resist any tendency to roll up or rise when striking a person.

A further object of the invention is to provide a fender having elements thereof so formed and arranged as to be disposed in a position to deflect a person struck out of the line of the track and car wheels.

An object of the invention also is to provide for mounting the fender in a manner so that the major elements of the fender will be maintained at a constant height above the track.

The invention resides in the novel features and combinations hereinafter more particularly described.

Reference is to be had to the accompanying drawings forming a part of this specification, in which similar characters of reference indicate corresponding parts in all the views.

Figure 1 is a side elevation of a fender constructed in accordance with my invention, showing the same applied to a street car and in position for use; Fig. 2 is a front view thereof; Fig. 3 is a partial plan view; Fig. 4 is a detail vertical section showing the means for securing the upper end of the supporting frame to the car; Figs. 5 and 6 are vertical sections on about the line 6--6 of Fig. 8, Fig. 5 showing the pivoted front portion of the fender partially moved rearwardly, as will occur when an object is struck, and Fig. 6 showing the complete rearward movement of the front portion, and an auxiliary deflector released and projected forwardly; Fig. 7 is a detail sectional plan view of the outer end of the fender, with the parts in the position shown in Fig. 6; Fig. 8 is a cross section on the line 8--8 of Fig. 6; Fig. 9 is a side elevation of the 55 fender in the raised position the net being omitted. Fig. 10 is an enlarged cross sec-

tion on the line 10--10 of Fig. 2; Fig. 11 is a vertical section showing details to be hereinafter referred to; Fig. 12 is a fragmentary sectional plan view of the elements shown in Fig. 11; Fig. 13 is a detail vertical section given to show the connection of the deflecting attachment; and Fig. 14 is a section on the line 14--14 of Fig. 13.

At the under side of the car A, near the front, a hanger 15 is secured, providing a transversely extending support for a longitudinally disposed frame 16, the side arms 16^a of which are spread a distance to be received in clips 17, which are pivoted to upright brackets 18 secured to the journal boxes a of the forward axles, so that the said frame 16 which carries the fender, as hereinafter explained, will respond to the vertical vibrations of the axles and thus be maintained at a constant level above the car track.

A cross bar 19 is carried in the forward end of the longitudinal frame bars 16, and uprights 20 are secured thereto, the uprights 20 being provided with tapering sockets 21 at the lower ends which are received on upright pins 22 on the cross bar 19. The upper ends of the standards 20 are united by a top cross bar 23, and over the bottom is a cross bar 23^a, so that the cross bars 23, 23^a and the standards 20 form the back frame of the fender, said fender back frame having a suitable net or preferably formed of wire mesh, extending from the bar 16 downwardly to a cross bar 24 held laterally secured to the net thus being inclined to the vertical so that a person striking the net will roll down over the plate 25 of the fender. The top bar 23 is supported on a transverse bar or beam 26 rigidly secured to the car, at the front, the connection being effected by a bolt 27 which passes through a transverse, curved slot 25^a in the rigid bar 26, the connection being such that the bolt 27 may move laterally to either side when the car takes a curve, the bar 25^a being struck from the center of movement of the front car truck. Thus in rounding a curve, the frame 16 and the fender will swing with the truck as a center, the bar 25^a and the hanger 15 affording the necessary guided movement. The bolt 27 projects below the bar 26 and is provided with a spring 27 between washers or collars 28 on the bolt, so that the back frame may yield to the vertical vibrations of the fender.

The fender proper comprises side arms 29, pivoted at their rear ends by a transverse pivot rod 30 which is received at its ends in forwardly projecting brackets 31 on the sockets 21, said side arms carrying the platform of the fender and its appurtenances, as hereinafter explained. Diagonal braces 32 are provided at the sides and pivoted at their lower ends to the side arms 29, near the front of the latter, and at their upper ends to the standards 20. The said braces are articulated, being provided with any suitable hinge 33, so that the braces may break downwardly at the center in response to the raising of the fender on the pivots 30, there being provided also a coupling bolt 34 sliding longitudinally in one section of each brace, and adapted to enter the companion section, the coupling bolts 20 being provided with heads 34^a for their convenient manipulation.

To hold the fender in the raised position, as in Fig. 9, hooks 35 are pivoted on the standards 20, advantageously by means of the upper pivots 36 of the braces 32, and are adapted to engage the lower pivots 36^a of the braces or other elements on the arms 29.

The flat form of the fender comprises side bars 37 and cross bars 38, the rear ends 30 of the side bars being provided with brackets or rearwardly projecting arms 39 pivoted on the rod 30. The members 39 are not rigid with the side bars 37, but are provided with forwardly extending spindles 40 that telescope in the said side bars, as shown in Fig. 12, compression springs 41 encircling said spindles and abutting at their forward ends against heads 42 on the spindles, and abutting at their rear ends against plugs 42^a in the bars 37. The arrangement permits the platform to move forwardly, as herein-after referred to. The front end of the platform is in the form of a vertically pivoted section, the side bars 44 being pivoted, as at 43, to have a vertical swinging movement on the side bars 37 of the platform. The said side bars 44 are also pivotally mounted, as at 29^a, on the forward ends of the supporting arms 29. The arrangement 50 is such that when the front section strikes a person or other obstruction, said section may rock downwardly and rearwardly, in response to the impact, from the normal position shown in Fig. 10, the springs 41 yielding, there being running wheels 45^a on a transverse shaft 45 at the lower ends of the bars 44 to contact with the track rails. The shaft 45 has bearings in brackets 44^a.

In order to lock the front section in the lowered rearward position, I provide a latch means that will automatically function. In the illustrated example this is made of latch rods 46 on a rock shaft 47 having bearings on the bars 44. The latch rods 46 extend diagonally upwardly and rearwardly and

are connected at their upper ends with a cross bar 48 which has sliding guided movement in keepers 49, secured to the under side of the side arms 29. Said keepers are provided with spring catches 50, the rear ends 70 of which are offset, as at 50^a. The arrangement is such that as the front section of the fender swings downwardly, the cross bars 48 will be engaged by the offset ends of the springs 50, as indicated in Fig. 6. 75

In connection with the pivoted front section of the fender, I provide a deflector, designated generally by the numeral 51, which is normally held restrained, but is automatically released and projected forwardly as the front section reaches the locked position. The deflector is formed, in the illustrated example, of tubular uprights 52 at the sides, and cross bars 53. Bolts 54 unite the deflector 51 to the side bars 44 of the pivoted front section, the said bolts passing through the bars 44 and having threaded engagement with cores 55 on which the tubular side bars 52 are adapted to have a limited turning movement, being 90 formed with arcuate slots 52^a (Fig. 14). Suitable spacing sleeves 54^a are fitted on the bolts between the bars 44 and the sleeves 52. The cross bars 53 are formed with wings or extensions 51^a at the ends. The said cross bars are articulated to break forwardly at the center, when not restrained, the overlapping ends 53^b being connected by a pivot bolt 56, and the several overlapped cross bars being spaced by sleeves 57. The cross 100 bars are extensible, being formed of telescoping members, of which one member 53^c of each bar telescopes within the mating member, and is under the influence of a compression spring 58 fitting in said mating 105 member, (see Fig. 7).

Normally the deflector 51 is restrained in a rearward position approximately flat against the pivoted section as in Figs. 1, 5 and 10. To hold the deflector in the rearward position, a latch is provided, which in the illustrated construction, consists of a sleeve 59 having a rearwardly projecting bracket 60, in which is a spring-pressed latch bolt 61, adapted to engage over a cross bar 62 rigid with the side bars 44 of the front section, or with other convenient fixed element on said front section. The latch bolt 61 engages over the bar 62 and prevents the springs 58 from projecting the 115 deflector attachment to the position shown in Fig. 7. To release the latch and permit the deflector section to be projected forwardly, a releasing device 63 is secured to the shaft 47, and has a forwardly projecting toe 64 in line with the latch bolt 61, for tripping said bolt. 120

In operation, as the pivoted front section of the fender moves downwardly and rearwardly, and the cross bar 48 of the arms 46 is 130

caused to travel in the keepers 49, the shaft 47 will be so rocked as to bring the toe 64 of the releasing device beneath the latch bolt 61, and as the cross bar 48 of the latch arms 46 is engaged by the springs 50, the toe will have tripped and raised the said latch bolt 61 clear of the cross bar 62, to permit the fender attachment to be projected forwardly by the springs 58. The action of the springs 58 is such as to cause the arms 53 to break in a forward direction at the bolt 56, the tubular side bars 52 rocking on the cores 55. The deflector will then present opposite inclines and roll the person struck, laterally, the side extension wings 51^a serving to deflect the person outwardly beyond the line of the wheels and tracks.

When the fender is to be raised, the front section with the deflector attachment thereon 20 may be swung upwardly on the pivots 29^a, 43, into alignment or approximate alignment with the platform 37, as indicated in Fig. 9, so that the folded and hooked fender may present a minimum of projection. It 25 will be noted that the keepers 49 are of a length to permit the arms 46 of the latch bar 48 to follow the aligned position of the pivoted front section.

The described construction affords a 30 practical means for carrying my invention into effect, and I would state in conclusion that I do not limit myself strictly to the mechanical details herein illustrated, since manifestly the same can be considerably 35 varied without departing from the spirit of the invention.

Having thus described my invention, I claim as new, and desire to secure by Letters Patent:

40 1. A car fender, comprising supporting members, a platform thereon, a front section on the platform pivoted to rock downwardly and rearwardly, deflector elements in front of said section and mounted for forward or 45 backward movement relatively to the said section, means to hold the deflector elements in rearward position against the front section, latch means to lock the front section in the rearward position, and means operative 50 by a rearward movement of the front section to release the holding means of the deflector elements.

2. A car fender, comprising a platform pivoted at the rear end to swing in a vertical plane, longitudinally ranging supporting members carrying the platform and mounted to swing in a vertical plane, and a pivoted front section on said platform movable to a position at a downward inclination 60 to the platform, or into approximate alignment therewith, said pivoted section having pivotal connection also with the said supporting members.

3. A car fender having a deflector attach- 65 ment at the front end provided with piv-

otally mounted elements presenting opposed ends having an articulated connection adapted to move to a projected position, means to restrain the deflector elements against forward movement and in approximately flat form with the articulated members in alignment, and means operable by impact against the fender, to release said deflector elements.

4. A car fender, having a deflector at the 75 front thereof, comprising pivotally mounted transverse members articulated at points between their ends to break in a forward direction from an approximately aligned flat position, and pivotally mounted at outer 80 portions thereof, means to restrain the transverse elements against forward movement, and means to release said restraining means by impact with an obstruction.

5. A car fender, having a deflector at the 85 front thereof comprising pivotally mounted cross bars formed of telescoping members, springs normally tending to separate said members, the cross bars being articulated to break in a forward direction and pivotally 90 mounted at outer portions thereof, means to restrain the cross bars against forward movement, and means to release said restraining means on impact of the fender with an obstruction.

6. A car fender having a deflector at the front thereof mounted to swing downwardly in a rearward direction upon receiving the impact of an obstruction, said deflector comprising pivotally mounted 100 transverse elements articulated to break in a forward direction to present opposite rearward inclinations from the axis of articulation, means to restrain the transverse elements against forward movement, and means to release the first-mentioned means upon a downward and rearward movement of the deflector.

7. A car fender, comprising a platform having a front section pivoted to swing in a 110 downward and rearward direction upon impact with an obstruction, and latch means to automatically lock the front section upon moving to the rearward position, said means comprising arms carried by the said front section at the rear thereof, a latch bar supported by said arms, and a latch engageable with said bar when in the rearward position.

8. A car fender, comprising a platform 120 having a front section mounted to swing in a downward and rearward direction, a deflector carried by said front section, the deflector comprising transverse members pivotally mounted at outer portions thereof to rock relatively to the said front section, and articulated between their ends to break in a forward direction, a latch carried by the said transverse members adjacent to the line of articulation, a member on the pivoted 125

70

115

120

125

130

front section with which the latch is adapted to engage to restrain the transverse members against forward movement, a latch means to lock the pivoted front section in the rearward position, and means on the said front section to release the deflector latch when the front section reaches the rearward locked position.

9. A fender having a front section pivoted to swing in a downward and rearward direction, a deflector comprising tubular side bars and transverse bars, cores on which the side bars are adapted to rock, said cores being rigid with the pivoted front section, 10 and the transverse bars of the deflector being articulated at the approximate center thereof to break in a forward direction, means to hold the cross bars against forward movement, and means to release the first-mentioned means upon a downward and rear-

ward movement of the pivoted front section.

10. A car fender, comprising fender members, an upright back frame mounting said fender members, a rearwardly extending 25 frame adapted for connection with a car truck, to swing with the latter, a guide adapted to be secured to a car and presenting a transversely curved slot, a bolt carried by said upright frame and movable in the 30 slot, and a spring on said bolt permitting said bolt to yield to the vertical vibrations of the upright frame.

In testimony whereof I have signed my name to this specification in the presence of 35 two subscribing witnesses.

ALBERT TREFETHEN GOOKIN.
